Walter A. Sloca
ATTORNEY

UNITED STATES PATENT OFFICE.

BENJAMIN F. HUBBELL, OF WATERBURY, CONNECTICUT, ASSIGNOR TO WORCESTER METAL GOODS COMPANY, OF WATERBURY, CONNECTICUT, A CORPORATION OF MASSACHUSETTS.

BAG-FASTENER.

1,324,155.

Specification of Letters Patent.

Patented Dec. 9, 1919.

Application filed December 10, 1918. Serial No. 266,153.

To all whom it may concern:

Be it known that I, BENJAMIN F. HUBBELL, a citizen of the United States, residing at the city of Waterbury, in the county 5 of New Haven and State of Connecticut, have invented a certain new and useful Improvement in Bag-Fasteners, of which the following is a specification.

My invention relates to sliding bolt 10 mechanism of the kind generally used on bags, suit cases and like articles for fastening swinging frame sections together, and its object is to provide a durable and economical sliding bolt mechanism of this 15 general type which can be made principally out of sheet metal without detracting from its strength or appearance. Another object of my invention is to provide sliding bolt mechanism which can be made up from a 20 minimum number of parts and in which the tendency for the parts to become loose and rattle will be reduced to a minimum.

I attain these and other objects of my invention in the device set forth in the following description and accompanying drawings in which like reference characters refer 25 to corresponding parts.

In the drawings:

Figure 1 is a perspective view of my device before it is attached to the frame section of a traveling bag;

Fig. 2, a longitudinal sectional view;

Fig. 3, a bottom plan view, and

Fig. 4, a transverse sectional view taken 35 on line α — α in Fig. 3.

My device generally comprises a box-like base member or casing 2 having a top face portion or wall 3, side walls 4, 4 and end walls 5, 5. The end walls 5, 5 are provided 40 with projecting lugs 6, 6 which serve to clench the casing to the top plate of one of the bag frame members. The top wall 3 of the casing is provided with an elongated, rectangular-shaped opening 7. The under 45 side of the top wall 3 of the casing is provided with two pair of alined recesses 8, 8 and 8', 8', the recesses of each pair extending away from the side edges of the slot 7. Sliding longitudinally upon the top wall of 50 the casing 2 is the slide proper or finger piece 9, the same comprising a rectangular box-like casing substantially of the general configuration of the lower or base casing 2 but slightly smaller than the latter. The 55 upper casing 9 is provided with end walls

10, 10 each of which has bent inwardly from its lower edge a pair of projecting lugs 11, 11. Resting on these lugs is a flat spring plate 12 of a surface area sufficient to substantially close the under side of the upper 60 casing 9 and having its body portion provided with a plurality of apertures 13, the purpose of which will presently appear. Depending from the under side of this plate is a locking post formed out of a single piece of 65 sheet metal folded midway of its extremities and brought together so as to form the post proper 14, the upper extremities of the metal being separated to form the side walls 15, 15 having spaced lugs 16, 16 projecting from 70 their upper edges respectively. These lugs 16, 16 pass through the apertures 13, 13 on each side of the center of the spring plate 12 and are bent outwardly against the top side of the spring plate and form brackets 75 or supports for holding up the locking post. The end edges of each of the side walls 15, 15 are slit and bent to form the outwardly projecting lugs 17, 17 which project at right 80 angles from the walls 15, 15 adjacent to each 80 end thereof but slightly below the top edges of these walls.

The parts are assembled in the following manner. The lugs 16 on the top edges of the locking post are passed through the 85 apertures 13 in the spring plate and bent outwardly at right angles. The spring plate is then inserted into the upper casing 9 so that its end edges rest on the lugs 11, 11 projecting from the bottom edges of each 90 end of the casing. The upper casing 9 is then placed over the opening 7 in the top wall 3 of the lower or base casing 2 so that the locking post extends downwardly there-through. The lugs 17, 17 at each end of the 95 locking post, which up to this time have not been bent out of the plane of the side walls 15, 15, are then turned outwardly at right angles to the walls, the spring plate 12 having been pulled downwardly by the lugs 16 100 a sufficient distance to enable the top edges of the lugs 17 to clear the under surface of the top wall 3 of the casing 2. The resiliency of the spring plate 12 thus holds the top edges of the lugs 17 close against the under 105 face portion of the top wall 3 and in this manner all of the parts are held together in their assembled position. When the upper casing 9 is given an endwise movement on the top of the lower casing 2 the upper 110

edges of the lugs 17 at one end of the post slide out of these recesses 8, 8', and at the end of the sliding movement of the upper casing, snap into the adjacent recesses 8, 8. 5 The recesses 8, 8 and 8', 8' serve to hold the casing at each end of its sliding movement. By utilizing a spring plate to support the locking post it is possible to make allowances for variations in the thickness of the 10 metal forming the casing and to draw the parts together in their assembled relation even though the same are not formed to exact dimension. Since the spring plate is seated on lugs in the casing and the lugs at 15 the top of the post are seated against the top of the spring plate it is possible to assemble the device by hand, thereby dispensing with the riveting and other machinery usually employed for assembling purposes. 20 The feature of having the top of the locking post made box shape so that its top walls are spaced apart where it joins the spring plate serves to prevent the post from tilting and breaking off as is sometimes the case 25 when the post is made of a single thickness of metal. The feature also of forming the post out of a folded piece of metal enables a light gage of metal to be used at the same time preserving the strength of the post 30 proper. While I have shown laterally bent lugs for guiding the post along the top wall of the base it is obvious that I may utilize any other guides when desirable. It should be noticed that the sliding casing presents 35 a flush surface on all sides since in the construction of my device it is not necessary to pierce the walls of the casing when fastening the parts together. The seating of the spring within the sliding casing enables 40 me to substantially conceal the same and also to eliminate the inner shell member usually employed for attaching the post to the casing.

While the device above described is the preferred embodiment of my invention yet 45 the same is susceptible to such modification as may fairly come within the scope of the appended claims.

Having now described my invention what I claim and desire to protect by Letters Patent is:

1. In a fastening device for bag frames and the like a base adapted to be secured upon one of the bag frame sections, a casing 55 slidably arranged upon said base, a spring plate mounted within said casing and a depending post connected with said spring plate.

2. In a sliding bolt mechanism for bag fasteners and the like a base adapted to be secured to one of the bag frame sections and having an opening therein, a member slidably arranged upon said base over said opening and a depending post carried by said member and extending downwardly through 65 said opening, the said post being formed out of a single piece of metal folded upon itself and having its extremities terminating at the upper end of said post.

3. In a sliding bolt mechanism for bag 70 fasteners and the like the combination with a base adapted to be secured to one of the bag frame sections and having an opening therein, a member slidably mounted upon said base over said opening and a depending post carried by said member and extending downwardly through said opening, the said post being formed out of a single 75 piece of sheet metal doubled upon itself and brought together to form the post proper 80 but separated at its upper extremity at its junction with said sliding member.

In testimony whereof I have hereunto set my hand this 5th day of December 1918.

BENJAMIN F. HUBBELL.
